(57) CLAIM

I claim the ornamental design for a hair band, as shown and described.

DESCRIPTION

FIG. 1 is a perspective view of the hair band showing my new design;

FIG. 2 is a front view thereof;

FIG. 3 is a left side view thereof;

FIG. 4 is a rear view thereof;

FIG. 5 is a right side view thereof;

FIG. 6 is a top plan view thereof;

FIG. 7 is a bottom plan view thereof; and,

FIG. 8 is an enlarged portion of the hair band drawn broken away for ease of illustration.
